UNITED STATES PATENT OFFICE.

GEORGE F. NELSON, OF BERKELEY, CALIFORNIA.

PUMP.

Application filed June 20, 1927. Serial No. 199,910.

This invention relates to improvements in vacuum pumps of the type disclosed in my pending application for patent filed October 30, 1923, Serial No. 671,725, the 5 primary object being to simplify, reduce in size, render more compact, and increase the efficacy of pumps of this type.

One of the objects of the invention is to provide an improved piston or impeller 10 which is provided with oil seal passages at the contact points thereof whereby oil contained in a chamber provided in the impeller is forced outward between the working surfaces to maintain an oil seal at all times, 15 the construction of the impeller also providing for longer bearings for the impeller shaft than is possible with other types of impellers and thereby improving the pump.

Another object is to provide an improved 20 pump chamber which has a removable end wall that facilitates the maintaining of an oil seal at the joint between the pump chamber and said wall and provides for the ready flow of oil into the pump chamber whereby 25 thorough lubrication of pump parts is insured.

Another object is to provide an especial 30 pump chamber and impeller construction which provides for the escape of gaseous fluid from the pump chamber above the liquid seal level thereby preventing spraying of the liquid into the pump chamber and out of the pump housing with the escaping gaseous fluid.

35 A further object is to provide an improved shutter having novel adjusting means providing for a quick and proper adjustment of the parts in assembling the pump and providing for adjustments to 40 compensate for wear, the shutter being of simple construction, inexpensive, and reliable in operation.

The pump of the invention is characterized by other improvements made out by 45 the special construction, interrelation, combination and association of various elements thereof wherein the pump as a whole is much more simple as to construction, more compact, consists of fewer parts, is cheaper 50 to make, and can be operated at less cost to produce a higher vacuum than other pumps of which I am aware.

With the above mentioned and other objects in view, the invention consists in the 55 novel construction and combination of parts hereinafter described, illustrated in the ac-

companying drawing, and set forth in the claims hereto appended, it being understood that various changes in the form, proportion, size and minor details of construction within the scope of the claims may be resorted to without departing from the spirit or sacrificing any of the advantages of the invention.

Referring to the drawing:

Fig. 1 represents a front elevation of the pump of my invention with the side wall of the pump housing and end wall of the pump chamber removed.

Fig. 2 represents a vertical sectional view 70 taken on the plane of line 2—2 of Fig. 1.

Fig. 3 is a fragmentary perspective view of the impeller.

The embodiment of the invention shown in detail in the accompanying drawing includes a housing 1 which in this instance is of rectilinear form and is provided with a removable wall 2. In one wall of the housing is an air intake opening 3 and an air outlet opening 4 into which are screwed 80 elbow fittings 3' and 4'.

Interiorly of the housing at the lower end thereof, is a pump chamber designated 5 and which consists of a substantially cylindrical wall 6 formed integral with the housing 1 and closed on one end or side by the wall 7 of the housing. The substantially cylindrical or arcuate wall 6 has the upper ends thereof spaced apart a distance, say equivalent to one-fourth of the circumference of said wall, leaving the upper portion of the pump chamber open. The other end or side of the chamber is closed by a removable, slightly resilient plate 8 held against the adjacent edge of the substantially cylindrical wall 6 by fastenings 8', said plate being spaced from the inner side of the removable wall 2 and leaving a space for oil which is contained in the housing. This provides an oil seal for the jointed parts of the pump. The plate 8 is provided with a comparatively large central oil intake opening 9, for a purpose which will be later described.

A shaft 10 is extended through a bearing 11 in the wall 7 and through the pump chamber 5 into a bearing 12 provided on the wall 2, this shaft being provided with means, not shown, whereby it may be driven by a motor or any other prime mover, not shown. A 105 suitable stuffing box 13 is provided where the shaft enters the bearing 11.

An impeller or piston 14, the peripheral contour of which is of rhomboid-ovate outline is keyed upon the shaft and operates within the pump chamber 5, the ends of said 5 impeller having a working fit with the arcuate wall 6 of the pump and the parallel sides of the impeller having a similar fit with end walls of the chamber. This impeller is hollow and provided with a central partition 15 having a hub sleeve 16 integral therewith. This partition provides chambers 17 and 18 interiorly of the impeller, which chambers communicate with one another through openings 19. The chamber 15 18 is communicated with the interior of the housing through the opening 9 which is of considerably greater diameter than the shaft 10. Oil contained in the housing 2 will enter the compartments 17 and 18 through the 20 opening 9 and lubricate the bearings for the pump. In this connection it will be noted that the bearings 11 and 12 are comparatively long and extend into the compartments 17 and 18. Thus by employing the 25 hollow piston the longer bearings may be employed and proper lubrication thereof is insured by oil contained in the chambers into which these bearings extend.

The contacting ends or faces of the impeller are concentric with the inner surface of the wall 6 for a distance, say approximately one-half inch in length, to provide an effective seal and a working fit of the impeller. To insure proper lubrication of the 30 contacting ends of the impeller and to provide an oil seal between these working faces, oil feed grooves 21 are provided in one side of the impeller so as to conduct oil from the compartments 17 and 18 out onto the periphery of the impeller. Oil forced outward in these grooves by centrifugal force and by 35 pressure against the body of oil contained in the housing passes into oil seal grooves 21' in the contacting end portions of the impeller thereby providing the desired oil seal. The periphery of the impeller has substantially parallel sides but each end portion is curved with an increasing radii from one side to the other so that there will be presented on the air discharge side of the impeller a shorter curve than on the opposite side. This provides for a comparatively 40 quick rise of the shutter against a slower return thereof and will prevent bouncing of the shutter. This shutter designated 22 is 45 adjustably and yieldingly held in contact with the periphery of the impeller and with the end 23 of the arcuate wall of the pump chamber. This shutter is carried on one 50 end of an arm 24 which is mounted on a pin 25, the pin being mounted in an adjustable support 26 which depends from a pin 27 projecting from the wall 7 of the housing. The adjustable support 26 is rotatably 55 mounted on the pin 27 and is held in pump chamber, the end 40, is disposed above 130.

adjusted position by set screws 28. The pin 25 may be raised and lowered on turning the support 26 on the pin 27. A spring cup 29 is pivoted as at 30 upon the arm 24 and receives the lower end of an expansion spring 31. The upper end of this spring bears against a pin 32 extended through a lug 33 which depends from the upper side of the housing, there being a plurality of openings 34 whereby the pin 32 may be disposed in different positions to vary the tension of the spring. The spring serves to yieldingly hold the shutter against the periphery of the impeller. By use of this adjustable mounting, the shutter may be quickly and easily adjusted to properly engage the periphery of the impeller in assembling the pump and adjustments may be likewise easily and quickly made at any time that it becomes necessary to compensate for wear 85 on these parts.

The intake opening 3 leads into a boss 35 provided on the wall 7 and said opening communicates with passages 36 and 37 terminating at their inner ends in openings 38 and 39 which are communicated with the interior of the pump chamber 5 at a point near the end 23 of the arcuate wall of said chamber, the opening 38 being disposed above the one 39 and close thereto. These 90 openings are adapted to be closed by the sides of the end portions of the impeller as shown in Fig. 1, so that when the end portions of the impeller move downward below said openings, air will be drawn through 95 said openings into the pump chamber by the suction action of said impeller and produce a vacuum in the passages 36 and 37 with which the opening 3 and elbow 3' are communicated. I prefer to employ two openings instead of one so that the impeller which is at all times bathed in oil, when moving past the upper opening 38 will wipe oil over the upper opening and thereby remove the oil from the impeller which would otherwise tend to film over the lower opening 39 thus preventing a filming over of the 100 lower opening and insuring the maintaining of a vacuum. If one opening is used, the oil film produced by the impeller wiping over said opening would be maintained throughout the movement of the piston and in some instances would not break down and would therefore prevent a suction or vacuum 105 action being produced by the pump. The two openings prevent this and insure a communication of the exhaust or vacuum line 110 with the pump chamber. By having the openings on the side instead of on the arcuate portion of the pump chamber, a more 115 effective sealing of these openings is insured and the destroying of the vacuum by back flow of air is prevented. It will be noted that one end of the arcuate wall 6 of the 120 pump chamber, the end 40, is disposed above 130.

the other end 23, said end 40 being above the normal level of oil within the pump. Thus, as the end of the impeller moves past the end 40, the air carried forward by the 5 piston in the pump chamber is released into the upper part of the pump housing above the level of the oil and the tendency of the oil to be forced back past the piston down into the pump chamber is prevented. Air 10 discharged from the pump chamber in this manner passes up and out through the discharge opening 4. To prevent spraying of oil out of the pump housing, a screen 41 is provided in the upper part of the housing as 15 shown in the drawing, this screen extending upwardly vertically in a lateral offset portion 42 of the housing and then downwardly against said offset portion 6, thus providing a double screened wall through which the 20 air must pass before discharging through the opening 4.

The pump is assembled with a suitable quantity of sealing fluid, preferably oil contained therein, the level of the oil being 25 sufficiently high to seal the joint between the wall 8 and the arcuate wall 6 of the pump chamber but being normally below the upper end 40 of said arcuate wall.

When the pump is used to produce a 30 vacuum, the desired connection is made with the elbow 3' and the pump set into operation with the impeller turning in a clockwise direction. As the ends of the impeller move past the openings 38 and 39, air will be 35 drawn into the pump chamber and forced around by the impeller and out between the impeller and the end 40 of the arcuate portion of the chamber into the upper part of the housing 2, from which it passes out to 40 the atmosphere through the opening 4. The shutter having a sealing engagement with the upper end 23 of the arcuate portion 6 of the pump chamber and also with the periphery of the impeller, prevents oil and 45 air from being drawn in by the impeller at any point above the openings 38 and 39. Curving of the ends of the impeller from one side of the impeller to the other on increasing radii provides for quicker lifting 50 action than a lowering action of the shutter and therefore insures an effective sealing of the pump chamber under all conditions of operation, the spring being held effective to force the shutter into place on the lowering 55 movement of the shutter due to this quicker action of the shutter.

Oil contained interiorly of the impeller is forced by centrifugal action and pressure on the oil, out through the small passages 21 60 into the grooves 21' and provides an oil seal between the working faces of the impeller and pump chamber at all times, thereby preventing any escape of air past the impeller back to the exhaust openings 38 and 39. 65 By having the upper end 40 of the arcuate

portion of the pump chamber disposed above the oil level, when the chamber is at this point, as the impeller moves past said point, the air discharges from the pump chamber without permitting oil to spray 70 downward past the impeller and into the lower part of the pump chamber.

The wall 7 is provided with a vertical oil groove 7' which extends from a point where its lower end communicates with the oil 75 compartment 17 in the impeller to a point substantially flush with the upper edge of the pump chamber. This groove feeds oil between the working faces of the wall 7 and impeller, also permits oil to flow upward 80 and into the pump chamber. When the pump is at rest the normal level of the oil is approximately in a plane corresponding to that of the upper side of the intake opening 38, there being a small quantity of oil 85 contained in the pump chamber on the upper side of the impeller. This oil, however, in the chamber is forced to the right of the end 40 of the arcuate wall 6 at the time of the escape of air between said end 40 and 90 the impeller so that said escape of air takes place at a point above the level of the oil as previously described.

The pump of my invention may be effectively used as a compression pump as 95 will be obvious on inspection of the drawing and foregoing description. The effectiveness of the pump for compression purposes is increased due to the presence of the oil, as above described, and the effective oil 100 seals provided by this oil and by the construction of the pump itself. These oil seal provisions prevent all possibility of leaks and back pressures and permit of high compression of gases with the pump of this invention. 105

I claim:

1. In a pump a housing adapted to contain a lubricating fluid and having intake and discharge openings, a substantially cylindrical pump chamber mounted within the housing and opening through the upper side of its arcuate wall into the housing, which chamber is provided through one end thereof with an intake opening communicating with the intake opening of the housing, said chamber also having an oil intake opening through one end wall thereof, a rhomboid-ovate impeller rotatably mounted within the chamber and having a working fit at its ends and on its opposite sides with the arcuate wall and the end walls of the chamber, which impeller is provided with an oil chamber therein communicating with the oil intake opening of said pump chamber, said impeller also having a passage extending from the oil chamber and opening at the periphery thereof and a shutter 115 yielding held in sealing engagement with the periphery of said impeller and with one end 120

of the arcuate wall of the chamber, the ends of said shutter also engaging the end walls of the chamber.

2. In a pump a housing adapted to contain
5 a lubricating fluid and having intake and
discharge openings, a substantially cylindrical pump chamber mounted within the
housing and opening through the upper side
of its arcuate wall into the housing, which
10 chamber is provided through one end thereof
with an intake opening communicating
with the intake opening of the housing, said
chamber also having an oil intake opening
15 through one end wall thereof, a rhomboid-
ovate impeller rotatably mounted within the
chamber and having a working fit at its ends
and on its opposite sides with the arcuate
wall and the end walls of the chamber,
20 which impeller is provided with an oil
chamber therein communicating with the oil
intake opening of said pump chamber, said
impeller also having a passage extending
from the oil chamber and opening at the per-
iphery thereof and a shutter yieldingly
25 held in sealing engagement with the per-
iphery of said impeller and with one end of
the arcuate wall of the chamber, the ends of
said shutter also engaging the end walls of
the chamber, the other end of said arcuate
30 wall of the chamber being disposed above
the plane of the normal level of the oil con-
tained in said housing.

3. In a pump a housing adapted to contain
35 a lubricating fluid and having intake
and discharge openings, a substantially cylindrical pump chamber mounted within the
housing and opening through the upper side
of its arcuate wall into the housing,
40 which chamber includes a removable end
wall spaced from the adjacent wall of the
housing and having an oil intake opening
therein, a rhomboid-ovate impeller rotatably
mounted within the chamber and having a

working fit at its ends and on its opposite sides with the arcuate wall and the end walls of the chamber, which impeller is provided with an oil chamber therein communicating with the oil intake opening of said pump chamber, said impeller also having a passage extending from the oil chamber and opening at the periphery thereof and a shutter yieldingly held in sealing engagement with the periphery of said impeller and with one end of the arcuate wall of the chamber, the ends of said shutter also engaging the end walls of the chamber. 45 50 55

4. A pump comprising a housing adapted to contain oil and having outlet openings, a substantially cylindrical pump chamber provided in the lower portion of said housing and comprising an arcuate wall closed on one side by one of the walls of the housing, a removable wall closing the other side of said arcuate wall, said pump chamber having an air intake opening extending through the first named side wall portion thereof, said removable wall having an oil intake opening therein, a shaft extending into the housing and through the pump chamber, and an impeller mounted on the shaft for rotation within the chamber with its ends in working contact with the arcuate wall of the chamber and the sides in working engagement with the sides of the chamber, said impeller having an oil chamber interiorly thereof with which chamber said oil intake opening communicates and being provided with an oil groove leading from the chamber to the periphery of the impeller and across each end of the impeller, and a shutter yieldingly held in engagement with the periphery of said impeller and with one end of said arcuate wall of the pump chamber, the ends of said shutter being engaged with opposite walls of said chamber. 60 65 70 75 80

GEORGE F. NELSON.
